Primary Examiner — Catherine Tuttle(74) *Attorney, Agent, or Firm* — Andrew C. Aitken(57) **CLAIM**

I claim the ornamental design for the mister and fan combination, as shown and described.

DESCRIPTION

FIG. 1 is a perspective view of the mister and fan combination showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines are included for the purpose of illustrating the portions of the mister and fan combination that form no part of the claimed design.
